UNITED STATES PATENT OFFICE.

ALVATIS A. BADGLEY, OF PLEASANTVILLE, IOWA.

CAMPER'S TABLE.

Application filed September 21, 1921. Serial No. 502,169.

To all whom it may concern:

Be it known that I, ALVATIS A. BADGLEY, a citizen of the United States, residing at Pleasantville, in the county of Marion and 5 State of Iowa, have invented a certain new and useful Camper's Table, of which the following is a specification.

The object of my invention is to provide a camper's table of simple, durable and comparatively inexpensive construction.

More particularly my invention relates to a folding camper's table adapted to be folded so that it will occupy a minimum amount of space and may be carried upon 15 the running board of an automobile.

Still another object is to provide a folding table adapted to be folded up for forming a case, the legs of the table being received within the case and the case being 20 capable of receiving a number of campers' articles such as the camp chairs, a small gasoline stove and any other camper's equipment.

With these and other objects in view my 25 invention consists in the construction, arrangement and combination of the various parts of my device, whereby the objects contemplated are attained, as hereinafter more fully set forth pointed out in my claims, and 30 illustrated in the accompanying drawings, in which:

Figure 1 is a view of the underside of the table, showing campers' chairs and a stove placed in position therein.

Figure 2 is a sectional view taken on the line 2—2 of Figure 1 showing how the legs of the table may be folded.

Figure 3 is a detail, sectional view taken on the line 3—3 of Figure 1.

Figure 4 is a perspective view of the table, ready for use.

Figure 5 is a detail, perspective view of one of the reinforcing members for the corners of the table.

Figure 6 is an end view of the table when folded and placed upon the running board of an automobile.

Figure 7 is a detail, sectional view showing how the table is folded.

Figure 8 is a central, sectional view taken through one of the camp chairs; and

Figure 9 is a side view of a pair of the standards of the chairs.

In the accompanying drawings I have used 55 the reference characters A and B to indicate a pair of similar table members which

are provided with reinforcing corners 10 as clearly shown in Figures 4 and 5 of the drawings.

The table members A and B are provided with the continuous flanges 11 and 12. The flanges 11 and 12 are arranged so that they are flush with one edge of the table members A and B and are spaced inwardly from the other three edges of the table members; 60 the purpose of which will be hereinafter 65 more fully set forth.

The side of the flanges which are flush with the edges of the table members A and B are arranged to abut against each other 70 and are connected together by a plurality of hinge members 13. Reinforcing L shaped members 14 are provided for connecting the ends of the flanges together.

In order to form the complete table I provide leg members 15 and 16 which are pivoted to one side of the flange 12 and the leg members 17 and 18 which are pivoted to one side of the flange 11. The legs 15 and 16 are connected to the flange 12 by 75 means of the bolts 19 which are provided with the thumb nuts 20 thereon.

The legs 17 and 18 are pivoted to the flange 11 by means of bolts 19 which have the thumb nuts 20 thereon. Each of the 80 legs is provided with a cut-away portion as at 21 so that they may fold one upon another as clearly illustrated in Figure 2 of the drawings.

The upper ends of the legs 15, 16, 17 and 85 18 are provided with a curved surface 22 so as to permit the legs to be swung on their pivots which are the bolts 19 when they are moved from inoperative to operative position.

The table members A and B and the flanges 11 and 12 when folded together will 90 form a complete case as illustrated in Figure 6 of the drawings.

In order to hold the two edges together I 100 provide hasp members 23. It will be understood that it is highly desirable for a camper to carry some chairs with him and yet not have them occupy much space.

In order to make it possible to place several chairs within the case formed by the folded table I provide knock-down chairs including a seat member 24 having a flange 25 on one side thereof adjacent to its outer edges. Legs 26 are provided for the seat members 24 which legs are connected together by a rod 27 having its ends screw 105 110

threaded so as to receive the wing bolts 28.

In order to hold the legs from sliding on the rod 27 I provide stop bolts 29.

The legs 26 are reinforced by wires 30 which run from the top of one leg to the lower end of the other leg and also diagonally, as clearly illustrated in Figure 1 of the drawings.

The upper end of the legs 26 are provided with notches 31 which receive the flange 25 of the seat 24 so that the legs are properly positioned for forming the complete chair.

In Figure 3 of the drawings I have shown a gasoline stove 32 which is provided with a flange 33 thereon; the flange 33 co-acts with a pair of holding members 34. The stove 32 may be slid in below the holding members for retaining it in position within the table when folded up.

In Figure 6 of the drawings I have shown a bracket for supporting the entire folded table and contents when carrying it on the running board of an automobile. 35 indicates the frame of the automobile and 36 the running board.

I provide a bracket 37 which is fixed to the frame 35 and passes below the running board and around it so as to form a raised portion 38. The bracket 37 is provided with a vertical standard 39 having a right angled extension 40 formed on its upper end.

The extension 40 is provided with a screw member 41; the parts are so arranged that the folded table may be slid in between the raised portion 38 and the vertical standard 39 of the bracket; the screw member 41 may then be tightened for engaging the entire table for holding it in position.

It will be seen that I have provided a knock-down camper's table which is very simple and which when folded will occupy a small amount of space, and at the same time serve as a convenient case for carrying other camping equipment.

Some changes may be made in the construction and arrangement of the parts of my camping table without departing from the real spirit and purpose of my invention, and it is my intention to cover by my claims, any modified forms of structure or use of mechanical equivalents, which may be reasonably included within their scope.

I claim as my invention:

1. A device of the class described adapted to be mounted upon an automobile comprising a bracket fastened at one end to the frame of said automobile, a portion adapted to rest on the running board of said automobile, a raised portion on the outer end and an upward extension on the inner end of said portion, a second portion at the end of said upward extension parallel with said first portion and a locking bolt in said last portion as and for the purposes stated.

2. A device of the class described adapted to be mounted upon an automobile comprising a bracket having a portion adapted to rest on the running board of said automobile, a raised portion on the outer end, and an upward extension on the inner end of said portion, a second portion at the end of said upward extension parallel with said first portion and a locking bolt in said last portion as and for the purposes stated.

Des Moines, Iowa, September 8, 1921.

ALVATIS A. BADGLEY.
